UNITED STATES PATENT OFFICE.

BRYCE P. GIBBS, OF LONG BEACH, CALIFORNIA.

PEN AND PENCIL HOLDER.

1,135,174.

Specification of Letters Patent. Patented Apr. 13, 1915.

Application filed May 2, 1914. Serial No. 835,925.

To all whom it may concern:

Be it known that I, BRYCE P. GIBBS, a citizen of the United States, residing at Long Beach, in the county of Los Angeles and State of California, have invented certain new and useful Improvements in Pen and Pencil Holders, of which the following is a specification.

This invention relates to the subject of pen and pencil holders, and has special reference to a novel construction thereof which will accommodate a plurality of pens and pencils, and also a calendar or other memorandum card.

It is desirable to have a container that completely houses the greater part of pens or pencils, so that they are protected from breakage, and at the same time held in a secure position to prevent them from falling out and becoming lost. Accordingly, the present invention contemplates a device that may be easily inserted in the pocket of a wearer or attached to a garment in such a manner that it will always be handy and ready for use, and at the same time protect the clothes from becoming soiled or stained from ink or pencil leads.

Another feature of the invention resides in its novel assembly of parts which are few, simple, and inexpensive while at the same time durable and serviceable, thereby rendering the invention capable of a practical commercial embodiment which renders the same particularly useful as an advertising novelty, though it will of course be understood that it is capable of being made in neat and attractive form which will increase its value as an article of personal wear.

With the above and other objects in view which will more readily appear as the nature of the invention is better understood, the same consists in the novel construction, combination, and arrangement of parts hereininafter more fully described, illustrated, and claimed.

A preferred and practical embodiment of the invention is shown in the accompanying drawings, in which—

Figure 1 is a plan view of the stamped metal blank from which the invention is formed. Fig. 2 is a plan view of the resilient deflecting leaf. Fig. 3 is a view of the calendar and memorandum card. Fig. 4 is a perspective view of the complete holder. Fig. 5 is a vertical sectional view. Fig. 6

is a rear elevation. Fig. 7 is a cross sectional view on the line 7—7 of Fig. 5. Fig. 8 is a cross sectional view on the line 8—8 of Fig. 5.

Similar reference characters designate corresponding parts in the several figures of the drawings.

In carrying out the present invention, any suitable material may be employed, though tin or similar pliable sheet metal is preferred, thus making the holder inexpensive to construct, and at the same time, light and serviceable. However, in some embodiments of the device the metal body may be covered with leather or other suitable ornamental material thus making it more attractive when manufactured for sale.

With particular reference to the construction shown in the several figures of the drawings, it will be observed that Fig. 1 shows a plan view of the container blank 1 from which the holder is formed. The said blank 1 is provided with a back wall portion 2 and a front wall portion 3, and an intermediate bottom wall portion 4. The back wall portion 1 is provided with the side wall attaching flanges 5 and also with the lining securing edges 6, while the front wall 3 is stamped to provide the wing-like side walls 7 and a lining clamping edge 8. The attaching flanges 5 on each side of the back wall portion 2, and the side wall 7 on the front wall portion 3, have provided therebetween laterally extended lining clamping ears 9 which extend from both sides of the bottom portion 4.

The resilient deflecting leaf 10, the blank for which is shown in Fig. 2, is provided at its top edge with laterally projecting attaching ears 11, the purpose of which will hereinafter more fully appear.

In assembling the container, a layer of felt or equivalent material 12 is preferably placed upon the area of the blank 1 bounded by the dotted lines *a*, *b*, *c* and *d* shown in Fig. 1, and the lining clamping edges 6 of the back wall portion 2 are folded over to clamp and protect the felt, as are likewise the lining clamping ears 9 carried by the bottom portion 4, and the edge 8 of the front wall portion 3. The side wall attaching flanges 5 of the back wall portion 2 are bent forwardly at right angles to the body of the blank, while the side walls 7 carried by the front wall 3 are bent rearwardly so that when the blank is doubled upon itself, to

bring the walls 2 and 3 into their proper relation, the side walls 7 will overlap with the flanges 5 so that they may be soldered or otherwise suitably fastened to hold the walls 1 and 2 together and thereby form the container pocket 13. The said side walls 7 terminate short of the bottom of the container leaving open spaces at each side of the bottom of the pocket so that broken lead and accumulations of dust may be easily removed. Arranged within said pocket 13, preferably near the lower end of the front wall 3, is a yielding pencil gripping member 14 which consists of a rubber tube 15 covered with felt or other similar material as clearly shown in Fig. 5 of the drawing.

Referring to Fig. 2 which shows the blank of the resilient deflecting leaf 10 having the attaching ears 11, it will be noted that in order to prepare this member for embodiment in the holder, it is necessary to bend the body of the same into the cross sectional form shown in Fig. 5, while the attaching ears 11 are bent forwardly at right angles to the body of the leaf. This deflecting guard 10 when thus formed is arranged within the mouth of the pocket 13 and secured in position by the attaching ears 11 being soldered or otherwise suitably secured to the upper portions of the side walls 7 of the front wall 2. The attaching ears 11 of the guard leaf 10 are of such a length that when the guard is placed in position in the mouth of the pocket that the wall 16 of said guard is spaced from the front wall 3, as shown in Fig. 5 to provide a card receiving slot 17. Thus, when a card, calendar, or other similar member 18 is inserted in the slot 17, the latter will be supported on the top of the pencil gripping member 14 so as to expose the top portion thereof to present a finger gripping portion to effect its withdrawal.

The present device is preferably made of such a size that it may be easily inserted in a vest pocket. However, the rear wall 2 of the device is provided with garment attaching means 19, thus making it possible to secure the holder to any garment, and on any desired portion thereof.

From the foregoing description, it is believed that it will be apparent that a novel and effective pencil holder has been devised, which in addition to holding pens, pencils, and similar articles, provides a pocket or receptacle for a calendar, memorandum slip, or advertising card. The provision of the deflecting leaf 10 in addition to providing a guide slot for the reception of a card deflects articles inserted in the pocket of the container toward the rear wall of the same, so

that there is no danger of the gripping member 14 being torn from its position.

I claim:

1. A pen and pencil holder including a container body formed of a single piece of sheet metal doubled upon itself to form a pocket and having lining clamping edge portions and oppositely disposed side walls and securing flanges, said side walls and flanges being arranged in spaced apart pairs on opposite sides of the bend of the blank and disposed in overlapping relation, and pencil gripping means within said pocket. 65

2. A pen and pencil holder including a container body formed of a single piece of sheet metal having front and rear walls initially in longitudinal alinement and in the same plane, side walls formed from said front wall, attaching flanges stamped with said back wall and spaced from said side walls, lining clamping ears projecting from the body in the space between the said oppositely disposed flanges and side walls, said single piece of metal adapted to be doubled upon itself and having its side walls and flanges bent into overlapping relation to form a pocket open at its bottom corners, and pencil gripping means within the pocket formed by the double piece of metal. 75

3. A pen and pencil holder including a pocket member formed of a single stamping of sheet metal doubled upon itself to provide a back wall portion and a front wall portion of less height than said back wall, side wall portions integral with the front wall and secured to the back wall portion, said side wall terminating short of the bottom of the pocket, a resilient deflecting leaf having laterally extending attaching arms adapted to be secured within the mouth of the pocket to the side walls so that the body of the leaf is spaced from the front wall, and yielding pencil gripping means within the pocket. 90

4. A pen and pencil holder comprising a container body having a resilient deflecting leaf secured within the mouth thereof and spaced from the front wall to form a slot, a yielding pencil gripping element arranged within the container across the lower portion of the front wall of said body, said yielding element and slot formed by the deflecting leaf and front wall of the body forming a card receiving pocket. 105

In testimony whereof I hereunto affix my signature in the presence of two witnesses. 110
